(57) **CLAIM**

The ornamental design for the tow rope as shown and described.

DESCRIPTION

FIG. 1 is a perspective view of the tow rope showing the new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top view thereof; and,

FIG. 7 is a bottom view thereof.

The dotted shading represents three-dimensional contour, is for illustrative purposes only, and forms no part of the claimed design. Symbolic break lines, shown in broken line, appear in the length of the tow rope. The break lines, as well as the appearance of any portion of the tow rope outside the break lines, form no part of the claimed design.
